UNITED STATES PATENT OFFICE.

EMIL BARTHES, OF SALINAS, CALIFORNIA.

HEEL PROTECTOR.

Application filed February 11, 1925. Serial No. 8,413.

To all whom it may concern:

Be it known that I, EMIL BARTHES, a citizen of the United States, residing at Salinas, county of Monterey, and State of California, have invented new and useful Improvements 5 in Heel Protectors, of which the following is a specification.

This invention relates to heel protectors for shoes. It is well known that in driving 10 automobiles the heel and rear portions of the driver's shoes rest on the floor of the car and become marred, scratched and worn. This situation is particularly objectionable to ladies since their shoes, being of a finer 15 texture, very quickly become soiled and worn from this cause. It is the object of my invention to provide a heel protector which can be readily snapped into place on the heel portion of shoes varying in size and shape 20 and which will fully protect the same from this objectionable wear.

In the accompanying drawing I have illustrated one specific embodiment of my invention, but it will be understood that the 25 invention can be otherwise embodied and that the drawing is not to be construed as defining or limiting the scope of the invention, the claims appended to this specification being relied upon for that purpose.

30 Referring to the figures of the drawing: Fig. 1 illustrates the use of my invention.

Fig. 2 is a perspective view of my improved heel protector.

Fig. 3 is a sectional view thereof taken 35 on line III—III of Fig. 2.

The heel protector of my invention comprises a leather casing 1 shaped to conform to the rear of a shoe and having a bottom heel portion 2 preferably sewed thereto. 40 This casing is constructed of fairly heavy and substantial material whereby the same will retain its shape and continue to stand up under rough usage. The inside of the casing is lined with a soft material as the 45 felt 3 illustrated whereby to protect the shoe against scratches and soiling.

The heel protector can be secured to the shoe in any manner desired. I prefer, however to provide means in connection therewith whereby the device can be very conveniently slipped on and off the shoe. As

illustrated, I mount a U-shaped leaf spring 4 on the inside of the casing 1 and secure the same thereto by rivets 5. The resiliency of the spring is such that the ends 6 thereof 55 normally spring toward each other in a manner to clasp the shoe therebetween.

The construction and use of my invention is believed to be obvious from the above description. When desiring to use the protectors, the driver merely snaps the same over the heel portion of her or his shoes, as indicated in Fig. 1. The spring ends 6 grip around the ball of the heel in a manner to hold the protectors quite firmly in place. 65 When leaving the driver's seat the protectors can be very conveniently slipped off without delay or effort. By the use of my invention, the driver's shoes are protected against being soiled and worn in the manner 70 well known and heretofore stated.

By referring to Fig. 1, it will be particularly noted that my improved heel protector is so constructed that the heel portion thereof does not accurately fit the heel of the 75 shoe. It is well known that the heels of shoes, and particularly those of ladies' shoes, vary widely in shape and size. By constructing the protector in the manner indicated, the same is adapted to be used on 80 shoes varying to a considerable degree in shape and size. The user is therefore not required to have a pair of protectors for each pair of shoes, but one pair of protectors can be used with all her shoes. It should 85 furthermore be noted that the spring 4 is so arranged above the heel portion that the ends of the spring engage against the sides and above the ball of the heel. In this manner the spring not only holds the protector 90 against displacement from the shoe, but the same also has a lifting effect on the protector in a manner holding the heel portion 2 thereof firmly engaged with the heel of the shoe. Thus, the spring acts both horizontally and vertically on the protector to hold the same firmly on the shoe.

Having thus described my invention, what I claim and desire to secure by Letters Patent is:

100 A heel protector comprising a casing having flexible side and rear portions formed

in one piece and adapted to loosely fit over and about the heel and rear portion of a shoe and a bottom portion adapted to fit over the bottom of the heel, the top and front portion of the casing being open and circumscribed by the marginal portion of the protector at the top of the casing and at the front edges of the casing and heel portion thereof, and spring means carried by the casing and adapted to resiliently engage the sides ¹⁰ of the shoe in a manner holding the casing against displacement from the shoe.

EMIL BARTHES.
